UNITED STATES PATENT OFFICE.

FRED B. DOWNS, OF NEW CASTLE, PENNSYLVANIA, ASSIGNOR TO PENNSYLVANIA IRON
AND STEEL PRODUCTS COMPANY, OF ELLWOOD CITY, PENNSYLVANIA.

METALLIC RECEPTACLE AND CHIME THEREFOR.

1,323,254.

Specification of Letters Patent.

Patented Dec. 2, 1919.

Application filed May 29, 1919. Serial No. 300,497.

To all whom it may concern:

Be it known that I, FRED B. DOWNS, a citizen of the United States of America, residing at New Castle, in the county of Lawrence and State of Pennsylvania, have invented certain new and useful Improvements in Metallic Receptacles and Chimes Therefor, of which the following is a specification.

- 10 This invention relates to metallic receptacles and chimes for the same, and it has for its object the provision of an improved structure of this nature, wherein the chime will be brought into such intimate engagement with the body of the receptacle as to form a fluid tight joint and, wherein the chime will serve as a reinforcing element to lend strength and rigidity to the receptacle, as a whole.
- 15 Further objects and advantages of the invention will be set forth in the detailed descriptions which now follows. In the accompanying drawings Figure 1, is an edge elevation of a chime illustrating its condition before application to the receptacle; Fig. 2 is a sectional view therethrough; Fig. 3 is a view showing the chime in elevation and the body of the receptacle in section after the chime has been applied to the receptacle; and Fig. 4 is a fragmentary face view of the chime.
- 20 Like numerals designate corresponding parts throughout the several figures of the drawing.
- 25 In carrying out the invention an annulus of L shape in cross section is first formed. One of the flanges or legs 5 of this annulus is adapted to fit snugly within a metallic receptacle, the walls of which are indicated
- 30 at 6. The other leg 7 of the annulus is of sufficient length to project beyond the walls 6, and the projecting part is provided with a swell 8 upon its lower or inner face. That

part of the leg 7 is then bent over upon the wall 6 of the receptacle to force the swell 8 into intimate engagement with the outer face of said wall and is rolled or otherwise forced into such tight engagement therewith as to constitute a fluid tight joint between the chime and the body of the receptacle and to firmly unite these two parts.

The necessary concavity 8' to receive the swell 8 is performed in the otherwise straight side wall 6, so that when the swell 8 is forced thereto the parts are firmly united, despite the fact that the wall 6 is uncrimped and comprises only a single thickness of metal.

It is to be understood that the invention is not limited to the precise construction set forth but that it includes within its purview whatever changes fairly come within either the terms or the spirit of the appended claim.

Having described the invention what is claimed is—

In a device of the character described the combination with a metallic body portion consisting of a single thickness of metal, of a chime comprising an angular flange 70 adapted to fit snugly down inside of said receptacle and a second flange integral therewith adapted to be bent inwardly over said body portion, the last named flange having a convex swell upon its inner face 75 and the wall of the body portion being provided with a concave recess for the reception of said swell, as and for the purposes set forth.

In testimony whereof I affix my signature in the presence of two witnesses.

FRED B. DOWNS.
